EX

OR D 18,525

DESIGN FOR AN ARM-REST FOR BARBERS' CHAIRS.

Design No. 18,525, dated August 14, 1888.

UNITED STATES PATENT OFFICE.

THEODORE A. KOCHS, OF CHICAGO, ILLINOIS.

DESIGN FOR AN ARM-REST FOR BARBERS' CHAIRS.

SPECIFICATION forming part of Design No. 18,525, dated August 14, 1888.

Application filed June 15, 1888. Serial No. 277,264. Term of patent 7 years.

To all whom it may concern:

Be it known that I, THEODORE A. KOCHS, a citizen of the United States of America, residing at Chicago, in the county of Cook and State of Illinois, have invented and produced a new and original Design for Arm-Rests for Barbers' Chairs, of which the following is a specification, reference being had therein to the accompanying illustration.

10 The illustration represents a perspective view of a barber's chair having my newly-designed arm-rest.

The leading feature of my design consists in a ball-shaped knob upon the forward end 15 of the arm-rest, which knob being vertically in line with the forward standard supporting the arm-rest, being in appearance a continuation of such standard.

A is the arm-rest, the forward end of which 20 has a downward offset, the square sides of which are ornamented with projecting panels.

The end of the arm-rest A is secured upon the forward standard, B, the upper portion of which is cylindrical and is ornamented with annular ogee beads. Upon the top of the forward end of arm-rest A is fixed a ball-shaped knob, C, being vertically in line with the cylindrical portion of front standard, B.

What I claim is—

The design for an arm-rest having a downward offset to its front end, with a ball-shaped knob on top of said offset portion and vertically in line with the front supporting standard of the arm-rest, substantially as described and shown.

35 In testimony whereof I affix my signature in presence of two witnesses.

THEODORE A. KOCHS.

Witnesses:

MOSES H. ROSENBLATT,
WILLIAM H. LOTZ.
